UNITED STATES PATENT OFFICE

WILLIAM SCHAAKE, OF PITTSBURGH, PENNSYLVANIA, ASSIGNOR TO WESTINGHOUSE ELECTRIC AND MANUFACTURING COMPANY, A CORPORATION OF PENNSYLVANIA.

INSULATOR-SUPPORTING STRUCTURE.

1,192,690.

Specification of Letters Patent. Patented July 25, 1916.

Application filed June 5, 1913. Serial No. 771,869.

To all whom it may concern:

Be it known that I, WILLIAM SCHAAKE, a citizen of the United States, and a resident of Pittsburgh, in the county of Allegheny and State of Pennsylvania, have invented a new and useful Improvement in Insulator-Supporting Structures, of which the following is a specification.

My invention relates to supporting structures for insulators, and it has special reference to insulator pins that are employed for high-tension transmission lines.

One of the objects of my invention is to provide an insulator pin of the above-indicated class, comprising relatively few parts, which shall be simple and cheap to manufacture and assemble and be easily adapted for a variety of service conditions.

Another object of my invention is to provide an insulator pin of great strength which shall be free from complicated and expensive parts and be so arranged that perfect alinement with the conductor to be supported may be secured with facility during the installation of the pin.

A still further object of my invention is to provide a supporting structure having a separable portion or thimble which is secured permanently in the body of the insulator for mounting it in position, the parts of which shall be inexpensive and may, therefore, be thrown away when a broken insulator is replaced.

A still further object is to provide an insulator-supporting pin having a separable base whereby it may be readily adapted for use with any size of base and for a variety of different types of mounting. In the prior art, insulator pins having separable thimbles have been employed, but as previously used, the thimbles were costly to manufacture and, moreover, the body portions of the pins were made as single castings, so that various sizes were necessary for the different sizes and shapes of cross-arms and other types of mounting.

According to my invention, I propose to overcome the difficulties and objections encountered in the prior art and to produce an insulator pin of simple structure which may be economically manufactured and installed and, moreover, may be utilized extensively under different service conditions.

In the accompanying drawings, Figure 1 is a view, partially in section and partially

in side elevation, of a structure embodying my invention; Fig. 2 is a side elevation of a portion of the structure shown in Fig. 1; Fig. 3 is a side elevation of the separable thimble; Fig. 4 is a view, partially in section and partially in plan, of the device, the section being taken along the plane IV—IV of Fig. 2, and Fig. 5 is a view in side elevation of a portion of a supporting structure adapted for a different type of mounting.

60

65

Referring to the drawings, the supporting structure comprises a plurality of insulator sections 1, which are united together to form a unit 2, and intermediate body member 3, a separable thimble 4, and a separable base 5.

70

The base 5 is substantially rectangular in form and has its bottom surface 6 curved upwardly to conform to the usual curvature of the upper portion of a cross-arm 7. The respective ends of the curved portion 6 of the base are provided with downwardly projecting flanges 8 for engagement with the side portion 7a of the supporting cross-arm 7, whereby said base 5 is held in position. The base 5 is, moreover, provided with a raised seat 9 having its center portion 10 slightly depressed to receive a correspondingly curved portion 11 of the intermediate body member 3. Openings or channels 12 are provided on opposite sides of the base 5 which communicate with the central depression 10 thereof for the purpose of draining off any moisture that may collect therein.

90

The intermediate member 3 is substantially cylindrical in shape and is provided with a plurality of flanges or tapering webs 14 which are located substantially 90 degrees from each other and connect a disk-like lower portion 15 with the cylindrical body portion of the member 3 for reinforcement and strength. The body portion 3 is, moreover, provided with a center recess 13 which reduces the weight and cost. The upper and lower end portions 16 and 17 of the member 3 are provided with tapped holes 18 and 19, respectively, for the purpose of receiving bolts 20 and 21, as will be hereinafter set forth.

95

The bolt 20 just referred to, constitutes, together with a tubular member or shell 22, the separable thimble 4. The shell 22 is cylindrical in form and is provided with a plurality of circumferential recesses or de-

100

105

110

pressions 24, a transverse opening 25 and a longitudinal centrally disposed opening 26, the upper portion 27 of which is preferably rectangular in shape to receive the square head 28 of the bolt 20 which projects through the central opening 26 and is adapted to be secured into the opening 18 of the intermediate body member 3. I find it most convenient and economical to employ a standard carriage bolt for this purpose because of its strength and cheapness.

The several insulator sections 2 may be of any well-known structure and, as my invention is not in any way limited to the specific form thereof, no detail description of the several insulator parts will be given. It will be understood that the insulator unit 2 may be composed of one or more insulator sections 1, as desired. The extreme upper surface of the insulator unit 2 is provided, in accordance with the usual custom, with a recess 29 to receive a conductor 30 which is to be supported. As shown, the several insulator sections 2 are disposed one above another and secured together by layers of cement 31 in the usual manner. The inner surface of the lower insulator section 1 is provided with a plurality of corrugations or threads 32 to assist in securing the cement 31 in position.

In assembling the various parts, the thimble 4, including the shell 22 and the bolt 20, is preferably permanently attached to the insulator unit 2 in the factory by means of cement 33 or other suitable material which is placed around the shell 22 and fills the circumferential recesses 24 and the transverse opening 25, for the purpose of holding the thimble 4 rigidly and permanently in position.

In installing the device upon a cross-arm 7, a base 5 is chosen that is adapted to the particular size and configuration of said cross-arm. After placing the base 5 in position, the intermediate member 3 is also positioned, and both members are temporarily held in place by the bolt 21 which projects through a suitable opening in the cross-arm 7 and engages the threaded recess 19 of the member 3. The insulator unit 2 and its associated thimble 4 are then secured tightly into place, and, in order to aline the groove or recess 29 with the conductor 30, it is only necessary to move the member 3, thimble 4 and the insulator unit 2, as a single unitary structure, upon the relatively stationary base 5. The whole device is then clamped rigidly in position by means of the bolt 21, as will be readily understood.

In case of breakage or puncture of the insulators 1, it is only necessary to remove them, with their associated thimble 4, and

to replace them with a similar structure, the thimble 4 being cast aside. It is evident that a power company may carry several different sizes of bases 5 to fit the different types of cross-arms used upon its system and may thus adapt a single size and type of insulator pin for any service condition, which is of material advantage in reducing the supply stock which would otherwise have to be carried.

Referring now particularly to Fig. 5, the body member 3 may be secured to a supporting U-shaped strap 35 by means of a suitable bolt 36, the strap 35 being secured to the upper end 37 of a pole or other supporting structure, in the usual manner. It will be noted that, in this so called "pole type" mounting, the base 5 is not employed, and the member 3 rests directly upon the strap 35.

Although I have shown and described a supporting structure having specific structural details and arrangement and location of parts, I desire it to be understood that all modifications thereof which do not depart from the spirit and scope of my invention are intended to be covered in the appended claims.

I claim as my invention:

1. The combination with an insulating unit having a transversely-extending groove adapted to receive a conductor, of a support therefor comprising a body member, a separable base having a seat for the body member, a separable thimble secured to the insulating unit, and separate and distinct bolts severally co-operating with the upper and lower portions of said body member for firmly securing said thimble upon the body member and said body member upon said base in order to aline the groove and the insulating member with the conductor to be supported thereon.

2. The combination with an insulating unit, of a support therefor comprising a body member and a separable thimble, said thimble consisting of a hollow shell portion having a rectangular opening and a transverse opening, a square-headed bolt received in the rectangular opening and having its shank projecting downwardly to engage said body member, and a binding cement flowed into and around said hollow shell portion of the thimble for securing said insulating unit thereto.

In testimony whereof, I have hereunto subscribed my name this 28th day of May, 1913.

WILLIAM SCHAAKE.
